UNITED STATES PATENT OFFICE

CHARLES F. STONE, OF UPPER DARBY, PENNSYLVANIA

SCORE SHEET HOLDER

Application filed June 10, 1929. Serial No. 369,877.

My invention relates to a score sheet holder and to playing card and pencil holding facilities in connection with it.

A purpose of my invention is to support a score sheet, and keep the same in a flat position.

A further purpose of my invention is to provide a playing card, score sheet and pencil container divided into compartments.

10 A still further purpose is to carry a roll of paper with or without scoring columns in a compartment in one slidable member and to expose and guide the sheet through and by another slidable and cover portion.

15 A still further purpose is to make a holder for a continuous score sheet which is of easy access for refilling.

Other purposes will appear in the specification and claims.

20 I have preferred to illustrate one structure only, with a slight modification, among the number in which my invention might be embodied, selecting forms which are practical, reliable and inexpensive of manufacture and which at the same time well illustrate the principles involved.

Describing in illustration and not in limitation and referring to the drawings:—

Figure 1 is perspective view of my improved holder.

Figure 2 is a perspective view similar to Figure 1 but with the cover partly removed.

Figure 3 is a perspective view similar to Figure 2 but with the cover removed and 35 the score sheet entirely exposed for use.

Figure 4 is a perspective view, looking in the opposite direction from that shown in Figure 3 showing the card and pencil compartments.

40 Figure 5 is a section taken on the line 5—5 of Figure 4.

Figure 6 is a section taken on the line 6—6 of Figure 1.

Figure 7 is a section taken on the line 45 7—7 of Figure 6.

Figure 8 is a section similar to Figure 6 illustrating a modification.

In the drawings similar numerals indicate like parts.

50 My invention comprises a carton 10 made

of three interfitting members—an outer cover 11, an inner cover 12 and a container 13, the container being adapted to slide within the inner cover 12.

The container 13 comprises a top 14, bottom 15 and sides 16 and 17 forming the outside structure. Intermediate the top 14 and 15, I inset U-shaped strips 18 or closed boxes in parallel 18', 19', if more convenient in manufacture, staggered and having their flat sides adjoining to form compartments 20, 21 for playing cards and 22, 23 for pencils or the like. The end of the U-shaped strip or box 18 or 18' is turned to form a wall 24 and the end of the strip or box 19 or 19' is turned to form a wall 25. These walls or partitions 24 and 25 allow for the exact placing of the playing cards in the compartments 20 and 21.

Some distance inwardly from the opposite end 26 of the container 13 I insert another partition 27. This partition serves two purposes, first to act as a stop for the pencils 28 (shown in dot-and-dash lines) and also to enclose the score sheet storage 29 on one side. 70 The other side is enclosed by the end 30 of the container 13. The storage supply 29 is guided at its ends by the sides, 16 and 17 of the container.

The container 12 is recessed along the top 80 14 at 31 to allow easy longitudinal passage of the score sheet 32.

The score sheet rests on the top 14 of the container and is held in position for use by the top 33 of the inner cover 12. The top 33 is open at 34 but is provided with inwardly extending borders or rims 35 and 36 at its sides and 37 and 38 at its ends to hold the score sheet securely in position exposed for use.

It will be clearly seen that the score sheet is held firmly in position and when the exposed portion of the sheet has been used the user can pull the end 32' and tear off any 95 desired amount of the paper by pulling against the edge 39 of the top 33.

I prefer to use a roll of paper as the storage for the score sheet as shown in Figure 6 but I may in some instances find it 100

desirable to use a folded strip which I show at 29' in Figure 8.

When it is desired to close the package with the cards, pencils and score sheet in place, the container is inserted, paper storage end first, into the open end 40 of the inner cover as then appearing as it is shown in Figure 4.

The inner cover and container together, 10 the entire structure of Figure 4—is then inserted into the outer cover 11 to make a very compact carton.

In use the storage score material is held in the back of the container and is withdrawn through the guiding space provided between the container and the inner cover where it is accessible for marking and at the same time is provided with a suitable backing against which marking may be effected.

20 Where this use is not desired the sheet may be torn off and removed to the table for use.

In view of my invention and disclosure, variations and modifications to meet individual whim or particular need will doubtless 25 become evident to others skilled in the art, to obtain part or all of the benefits of my invention without copying the structure shown, and I, therefore, claim all such in so far as they fall within the reasonable spirit 30 and scope of my invention.

Having thus described my invention, what I claim as new and desire to secure by Letters Patent is:

1. In a playing card holder and score 35 sheet, a holder and inner container having a recess in the back forming a compartment, open at the back, an outer container longer than the inner container, forming a closure for the back of the recess in the holder and 40 recessed to provide side and end guides for score material and an opening for marking upon the score material when the score material has been partly withdrawn and a cover for the outer container applied to it from the 45 opposite end to that from which the outer container is applied to the inner container.

2. In a playing card and score sheet holder, an inner container having a recess at the back for holding score material in 50 extended sheet form, the recess being open rearwardly, an inner cover open at one end closing the rear of the recess and having an opening to provide accessibility for the sheet material and to guide it as it is withdrawn 55 lengthwise and an outer cover within which the inner cover is inserted to close the open end of the inner cover.

CHARLES F. STONE.
